UNITED STATES PATENT OFFICE.

CHARLES E. ROGERS, OF DETROIT, MICHIGAN.

FILLING-MACHINE.

1,279,161.

Specification of Letters Patent. Patented Sept. 17, 1918.

Application filed July 3, 1916. Serial No. 107,323.

To all whom it may concern:

Be it known that I, CHARLES E. ROGERS, a citizen of the United States, residing at Detroit, county of Wayne, State of Michigan, have invented a certain new and useful Improvement in Filling-Machines, and declare the following to be a full, clear, and exact description of the same, such as will enable others skilled in the art to which it pertains to make and use the same, reference being had to the accompanying drawings, which form a part of this specification.

This invention relates to machines for filling bottles, cans, or other receptacles, and its object is a device whereby a definite amount of milk or other fluid may be placed in bottles or other receptacles. Another object of the invention is a device for filling bottles or the like with milk in such manner that the foaming thereof caused by delivery into the receptacle is reduced to a minimum. An additional object of the invention is a device of the character stated in which a plurality of receptacles may be simultaneously filled with an equal amount of fluid.

In many machines of this class, the filling of the receptacle depends upon the opening of a valve to allow a flow of fluid into the receptacle and evidently any inaccuracy in the opening of any of the valves results in some of the cans not being properly filled. A novel feature of this invention is involved in the means involved in automatically measuring the fluid prior to its delivery into the receptacle whereby all cans or bottles receive exactly the same quantity.

These and other objects and the several novel features of the invention are herein-after more fully described and claimed and shown in the accompanying drawings in which—

Figure 1 is a vertical longitudinal section of my improved filling machine.

Fig. 2 is a vertical transverse section thereof.

Fig. 3 is a cross section taken on line $x-x$ of Fig. 1.

Fig. 4 is a section taken on line $y-y$ of Fig. 1.

Fig. 5 is a detail of the measuring cup.

Similar characters refer to similar parts throughout the drawing and specification.

The device consists of tank 1 supported on a frame 2 to which is attached the legs 3. A sub-frame 4 is also secured to the legs

midway between the frame 2 and the lower end of the legs.

The tank 1 is adapted to be filled to a predetermined level and for filling the tank a supply pipe 5 is utilized provided with a float controlled valve as may be understood from Fig. 1 to prevent an overflow of fluid in the tank. In each corner of the two frames 2 and 3 is provided bearings for the rods 6, 6 etc., which are adapted for vertical movement in vertical bearings provided at each of the four corners of the frames. On the upper ends of the rods is carried a frame 7 held on the rods by the adjusting nuts 8. This frame 7 supports a series of cups 9 and in the device here illustrated, there are 24 of these cups movable with the frame work. A series of tubes 10, one for each cup, is secured in the bottom of the tank having their upper ends above the normal level of the fluid in the tank and the lower ends thereof extending a short distance below the bottom of the tank. The cups are adapted to slide on the tubes and are held in alinement therewith by means of a yoke 11 in each instance attached to the open ends of the cups and a bearing 12 at the lower end which is provided with one or more annular grooves 13, as shown in the detail in Fig. 6, adapted to prevent leakage about the tube.

As is shown more clearly in Fig. 2 each rod 6 is threaded near the lower end to receive the nuts 14 and 15 and between those nuts is secured the apertured end of the arms of a V shaped bracket 16.

There are two brackets 16 on opposite sides of the machine as will be understood from Fig. 3, each of the arms of each bracket being secured to the ends of the two rods on the corresponding side of the machine. At the lower end these arms are united in a block having a portion 17 riding in the ways 18 provided on each side of the machine for each block respectively. A shaft 20 extends transversely of the machine and is carried by these blocks and by means of the guideways 18 the shaft and brackets are held to move in a vertical plane. A horizontal shaft 21 is carried in bearings in the frame member 4 on one side of the machine and arms 22 are provided secured to the shaft 21 and having slotted ends 23 through which the shaft 20 passes. As may be seen clearly in Fig. 1 an operating lever 24 is provided on one end of the shaft by operation of which

the arm 22 of the lever 24 moves the shaft 20 in a vertical plane. By pulling the lever 24 downward, the shaft 20 and the V shaped brackets are raised forcing the rods 6 upward in the bearings therefor and raising the cups 9 on the tubes 10; liquid begins to discharge through the tubes and the quantity of fluid discharged depends upon the height to which the cups are raised. This height 10 may be regulated in various ways as by means of threaded nuts 25 on each rod and engaging against the lower face of the upper rectangular frame as may be understood from Fig. 2. By varying the position of the 15 nuts on the rods the cups may be raised to a greater or less height as may be desired and thus the quantity of fluid discharged accurately measured.

A stationary frame 26 may be supported 20 on the frame work 4 as shown clearly in Fig. 1 which is provided with the angle iron side members 27 and carries a series of rollers 28. A tray 29 may be run into the machine on these rollers and the tray practically fits between the vertical side members 27 so that 25 the tray is positioned in the frame and it will be readily understood that a stop should be provided so that the tray when moved into the machine against the stop is accurately positioned for the purpose hereinafter 30 stated. The tray is of exactly the right size to carry a number of receptacles equal to the number of tubes 10 and centered according to the centering of the tubes 10. Thus, 35 on moving the tray into position in the machine, the receptacles are placed directly beneath the lower ends of the tubes and it is to be understood that these receptacles may either be the common well known cans for 40 condensed milk or may be bottles, either of paper or glass, or other material for holding natural milk. The receptacles being thus positioned directly beneath the lower ends of the tubes, the material flowing from the 45 tubes will flow into the cans or bottles as the case may be.

Some fluids upon being discharged into bottles or cans have a tendency to foam on flowing from the tubes and I have discovered 50 that, if the discharge end of the tube be near the bottom of the receptacle, the foaming is reduced to a minimum. For this purpose I have provided a reciprocatable frame 30 having four legs 31 one in each corner adjacent 55 the reciprocating rods 6 as will be readily understood from the drawing. The frame 30 is provided with two lugs 50 on opposite sides riding in the ways 18 heretofore described. To this frame member or 60 plate 30 are secured a series of tubes 32 telescoping on the lower ends of the tubes 10. When the frame 7 carrying the measuring cups is in its lowermost position, as in the filling of the cups as shown in Fig. 1 65 the frame 30 is in its uppermost position

with the lower ends of the tubes 32 attached thereto above the open ends of the receptacles allowing plenty of room for moving the tray with the receptacles thereon into the machine. On raising the rods 6 and measuring 70 cups to discharge the fluid into the tubes 10, the frame 30 moves downwardly to position shown by full lines in Fig. 2 moving the ends of the tubes 30 into each receptacle near the bottom thereof. After the flow has 75 started the remaining fluid from the cups is discharged into the receptacles below the level of the fluid therein whereby the foaming is reduced to a minimum.

In order that the frames 7 and 30 may 80 simultaneously move in opposite directions as described, each of the rods 6 are provided with rack teeth 33 and each of the rods 31 are provided with similar rack teeth 34. Supported by brackets on the frame work on 85 opposite sides thereof are provided shafts 35 and 36 and attached to these shafts in position to engage the rack teeth 33 and 34 respectively are gear wheels 37 and 38. There are four pairs of similar gear wheels for each 90 of the four rods 6 and 31. It is to be noted that the gear 37 is considerably larger than the gear 38, the purpose being to allow the frame 7 and the measuring cups to move a greater distance than is required of the 95 frame 30 and tubes thereon. This movement, however, depends practically entirely on the height of the receptacle into which the fluid is discharged. With cans of little height as here shown, the movement of the 100 frame 30 and tubes thereon may be practically about half the movement of the frames 7 and measuring cups. If bottles are to be used into which the fluid is to be discharged the parts may be designed for practically 105 equal movement. In such event only a single gear wheel is necessary between the rods 6 and 31. In either case movement of the rods 6 in either direction causes a movement of the rods 31 and the connected parts 110 in a reverse direction. From the above it will be readily understood by those skilled in the art that any degree of variation as to movement of the frames 7 and 30 may be provided for as may be desired.

By this arrangement of gears and racks the frame 30 and connected parts provides a counter balance for the frame 7 and connected parts but as the frame 7 and connected parts are considerably greater in weight 115 than the frame 30, a counter-weight 40 may be provided on a rod 41 pivoted to the frame at 42 and having a forked end 43 engaged about the shaft 20 as shown in Fig. 2. By thus counter-balancing the frame 7 and rods 120 6 the same may be reciprocated with very little effort by means of the operating lever 24.

Undoubtedly several methods of bringing the discharge ends of the tubes in close prox- 130

imity to the bottoms of the receptacles during the discharge interval will occur to those skilled in the art. I have here shown only a single method of producing such result, 5 but in this respect I do not desire to limit myself to the construction shown.

In operation and with the parts in position shown in Fig. 1, the cups are filled by reason of the open ends thereof being below the 10 normal level of the fluid. The tank is made considerably larger in area than that occupied by the measuring cups as otherwise the tank would overflow at the time of immersion of the cups after being emptied. Upon 15 depressing the lever 24 the filled cups will be raised to position shown in Fig. 2 and the contents thereof discharged to the point determined by the adjusting nut 25. As the measuring cups are raised the tubes 32 are 20 moved downward into the receptacles as heretofore stated and also as the measuring cups are raised the float will open the valve in the supply pipe 5 and the tank begin to fill. This operation may be repeated as rapidly 25 as the filled receptacles and trays may be removed from the machine and unfilled receptacles replaced therein.

From the foregoing description it becomes evident that the device is comparatively simple 30 in operation requiring but little or no ingenuity on the part of the operator, after the machine has once been set, to fill each of the receptacles with exactly equal quantity of fluid at each operation.

35 Having thus briefly described my invention its utility and mode of operation what I claim and desire to secure by Letters Patent of the United States is—

1. In apparatus of the character described, 40 a tank for receiving fluid, means for maintaining the level of the fluid therein, a tube mounted therein having an inlet end above the normal level of the fluid and a movable discharge end projecting through 45 the tank, means for positioning a receptacle to be filled below said discharge end, a measuring cup reciprocably mounted on the tube adapted to be alternately filled by immersion in the fluid in the tank and to discharge 50 the same through the inlet end of the tube and means whereby the discharge end of the tube is moved into close proximity to the bottom of the receptacle during the discharge of the fluid thereinto.

55 2. In apparatus of the character described, a tank for receiving fluid, means for maintaining the level of the fluid therein, a plurality of tubes mounted vertically in the tank having the inlet ends at the same 60 height about the normal level of the fluid in the tank and provided with similar movable discharge ends projecting through the tank, a measuring cup reciprocably mounted on each tube and adapted to be alternately 65 filled by immersion in the fluid and to dis-

charge the same as the measuring cup is raised on the tube, means for positioning a series of receptacles below the discharge ends of the tubes, and means for moving the discharge ends into the receptacles at 70 the time the measuring cups are raised whereby the fluid is delivered into the receptacles near the bottom thereof.

3. In apparatus of the character described, 75 a tank for receiving fluid, means for maintaining the level of the fluid in the tank, a tube mounted therein having an inlet end above the normal level of the fluid in the tank and a discharge end projecting there-through, a measuring cup reciprocably 80 mounted on the tube and adapted to be alternately filled by immersion in the fluid and to discharge the same through said inlet end, a tube reciprocable on the discharge end of the discharge tube, means for positioning a receptacle below said reciprocable tube and means whereby on movement of the measuring cup to discharge the fluid the reciprocable tube is inserted into the 85 receptacle. 90

4. In apparatus of the character described, 95 a tank for receiving fluid, means for maintaining the level of the fluid therein, a plurality of tubes mounted vertically in the tank having their inlet ends at the same height above the normal level of the fluid and provided with similar discharge ends projecting through the tank, a measuring cup reciprocably mounted on each tube 100 adapted to be alternately filled by immersion in the tank and to discharge the same as the cups are raised on the tube, means for positioning a series of receptacles below the discharge ends of the tubes, a series of telescoping tubes, one on each discharge 105 tube, and means whereby the said telescoping tubes may be moved downward into the respective receptacle as the measuring cups are raised to discharge the fluid into the tubes. 110

5. In apparatus of the character described, 115 a tank for receiving fluid, means for maintaining the fluid at a predetermined level therein, a plurality of tubes mounted vertically in the tank having inlets at the same height above the normal level of the fluid therein and having similar discharge ends extending through the bottom of the tank, a measuring cup reciprocably mounted on each tube adapted to be filled by immersion 120 in the fluid and to discharge its contents as the measuring cup is raised on the tube, a frame to which the cups are secured, means on the frame for adjusting the position of each cup vertically on the tube, the 125 frame having standards provided with rack teeth, a gear meshing with each rack of each standard of the frame, means for raising the said frame and rotating the said gears, a series of telescoping tubes, 130

one for each discharge tube, a frame to which the telescoping tubes are secured, the said frame for the telescoping tubes having standards corresponding in number to those of the measuring cup frame and also being provided with gear teeth, a gear meshing with each rack of the last named frame, the said gear being fixed to the shaft of the gear for the measuring cup frames and rotatable therewith, the gear for the measuring cup being greater in diameter than the gear for the tube frame and the gears for the tube frame operating to move the tube frame downward at the time the cup frame is raised and vice versa.

6. In apparatus of the character described, a tank for receiving fluid, means for maintaining the level of the fluid therein, a plurality of tubes mounted vertically in the tank having inlet ends at the same height above the normal level of the fluid therein and provided with similar discharge ends projecting through the bottom of the tank,

a measuring cup reciprocably mounted on each tube adapted to be filled by immersion in the fluid and to discharge the same as the measuring cup is raised on the tube, a frame to which the cups are secured, means on the frame for adjusting the position of each cup vertically on the tube whereby all of the cups may be positioned with the open ends in the same plane, means for reciprocating said frame whereby the cups are simultaneously operated, means for positioning a series of receptacles below the discharge ends of the tubes, a series of telescoping tubes, one for each discharge tube and reciprocable on discharge ends thereof, a frame to which each of the telescoping tubes are secured, and means whereby, when the measuring cup frame is raised, the frame for the telescoping tube is lowered and the tubes inserted into the respective receptacles.

In testimony whereof, I sign this specification.

CHARLES E. ROGERS.
